UNITED STATES PATENT OFFICE.

CHARLES HAMANN, OF PORT CHESTER, NEW YORK.

BOTTLE-WASHER.

1,269,077.

Specification of Letters Patent. Patented June 11, 1918.

Application filed August 21, 1914. Serial No. 857,882.

To all whom it may concern:

Be it known that I, CHARLES HAMANN, a citizen of the United States, residing at Port Chester, county of Westchester, State of New York, have invented certain new and useful Improvements in Bottle-Washers, the following being a full, clear, and exact disclosure of the one form of my invention which I at present deem preferable.

For a detailed description of the present form of my invention, reference may be had to the following specification and accompanying drawings, forming a part thereof, in which—

Figure 1 is a plan and

Fig. 2 is a front elevation partly in section of the upper portion of my machine,

Fig. 3 is a section thereof,

Figs. 4 and 5 show details.

Fig. 6 is a plan view illustrating the invention.

One feature of my invention relates to a device for adjusting the position of the bottle-turning belt with respect to the size of the bottle that is to be washed without at the same time changing the belt tension, while the belt-tension can be adjusted without altering the relation of the belt to the line of the bottles. I have also devised a new means of securing the bottle spindles to the carrier wheel and have provided a special and separate brush for washing the necks of the bottles externally. Other features of invention will be specified in the claims.

Referring to Fig. 3 of the drawings, A represents the horizontal base of my machine in the center of which is secured a conical stud B on which rotates the carrier-wheel C. This wheel has a hollow rim in which at intervals are barriers C¹ (see at the right of Fig. 1) that limit the flow of water in the hollow rim. The spokes of the carrier-wheel are hollow and serve to connect the interior of the hollow rim with a water space C² in the hub C³ of the wheel. The stud B on which the wheel hub C³ is journaled is shown in detail in Fig. 5, being hollow and supplied with water under pressure by means of the pipe B¹. On the stud B are two holes b, b which register with the water-space C² in the hub C³. By this means water is delivered into the hollow wheel-rim and passes thence upward into the bottle spindles from which it shoots into the inside of the several bottles on the respective spindles.

One of the bottle spindles is shown at I, the details thereof being shown in Fig. 4. The lower end of each spindle terminates in a plug i² fitting snugly in a hole through the spindle-seat on the rim of the carrier-wheel. A seating flange i projects horizontally from the spindle and rests on a rubber washer i³ on the spindle-seat of the carrier-wheel. A spring-holder K loosely surrounds the spindle just above the seating-flange i, and bears thereupon, being bent down along the outside of the wheel-rim, and terminating in a bearing-bend which rests on the under side of the wheel-rim directly opposite and in line with the spindle. By this means it is a simple matter to change the spindles for bottles of different sizes, since it is only necessary to lift the spindle until its plug-end clears the hole in the wheel-rim, the spring-holder K yielding sufficiently for that purpose, and then remove the spindle together with the spring-holder from the rim. The carrier-wheel is rotated by a gear-wheel c¹ on the hub C³, with which meshes a pinion c² on a jack-shaft driven by sprocket chain c³ from a vertical shaft E¹ in the standard D. The vertical shaft E¹ is driven by bevel gearing from the pulley-shaft E.

The brush-wheel F is carried on a vertical shaft F¹ mounted in brackets projecting from the stud B at the bottom and from standard D at the top of shaft F¹. The journal boxes for the shaft slide in slots in their respective brackets and are adjusted in position by screws. The brush-wheel has a smooth-faced rim on which are bolted vertical wooden-back brushes and it is rotated by a sprocket-chain connection from the shaft E¹ aforesaid. The bottles, which are supported as shown by the spindles I of the carrier-wheel, pass somewhat tangentially along the face of the brush-wheel as clearly appears in Fig. 1 and are thoroughly scrubbed by the brushes which rotate in the opposite direction to the bottles. At the same time the bottles pass under the stationary brushes G, G by which the bottoms of the bottles are scrubbed. As each bottle approaches the scrubbing point, it is automatically lifted up on its spindle by means of a lifter I¹ on which the head of the bottle rests. Each lifter I¹ is mounted on a vertical rod I² (see Fig. 2) which has a roller at its lower end that runs onto a lifter-plate I³, as it approaches the scrubbing-point and thereby causes the lifter I¹ to rise a short dis-

tance carrying the bottle with it. The result is that the scrub-fin on the spindle I within the bottle rubs against the inside of the neck of the bottle to clean it. As each 5 lifter rides off the plate I², it drops down to its normal level, and the scrub-fin which is of rubber bends over at its tip to allow the bottle to also descend to its normal position.

I have moreover provided an outside neck-10 brush H (see Fig. 2) which is upheld by a shank h that hooks over one of a series of hooks h¹ on the standard D. From the back of the brush H projects, at a right-angle thereto, a bar h³ on which is a weight h² that 15 can slide in or out on the bar h³, to adjust the pressure which it exerts on the brush H to hold the brush against the neck of the bottle.

The next feature to be noted is the bottle-20 turning pressure-belt O, by which the bottles are held against the brush-wheel F (see Figs. 1 and 2) and by which the bottles are caused to rotate. I have devised means by which this belt may be bodily adjusted toward or from the brush-wheel F without disturbing its tension adjustment, or, conversely, can have its tension adjusted without disturbing its relation to the bottles and to the brush-wheel. This belt O is extended 25 between the pulleys O¹, O², which are shown respectively at the left and right of Fig. 1 and at the right and left of Fig. 2. The pulley O¹ is fast on shaft L¹ which is journaled in the bearings m, m which are carried 30 respectively by the top and bottom arms m¹, m¹ of a C-shaped yoke M. The arms m¹, m¹ are curved inwardly (with respect to the plane of the upright portion of yoke M) toward the carrier-wheel C, as appears in the 35 plan view in Figs. 1 and 6. The yoke M is itself pivoted, at top and bottom, in the clevis jaws j¹, j¹, which are carried on the ends of bracket arms j¹, j¹, being offset therefrom and the bracket-arms j¹, j¹ are carried 40 in turn by an upright shaft J¹ which is journaled in lugs on the standard D. By this means the swinging of the bracket-arms j¹, j¹ will bring the pulley O¹, together with the yoke M on which the pulley O¹ is journaled, 45 nearer to or farther from the carrier-wheel C and the bottles thereon. The position of the bracket-arms j¹, j¹ is fixed by the slotted link R¹ secured to one arm of the bracket P on the standard D. In Fig. 1, for example, 50 the pulley O¹ and the belt O thereon are so adjusted that the belt will just bear tangentially on the bottle S; but it may be adjusted in farther to also bear on the adjacent bottles S¹ on either side of bottle S. On the 55 other hand, it may be adjusted out to take in bottles of a larger size. The tension of the belt O is adjusted by the turning of the yoke M in the jaws j¹, j¹, the adjusting screw m³ being provided for that purpose between the 60 curved arm m¹ and the bracket arm j¹. By

turning this screw the pulley O¹ may be adjusted in or out with respect to the bracket arm. The pulley O² is similarly fixed on a shaft L², but that shaft is not journaled in a yoke like shaft L¹, but is journaled directly 70 in bracket-arms j², j² (corresponding to bracket-arms j¹, j¹) by means of bearings j⁶, j⁶. Thus the pulley O² can be moved in and out with respect to the bottles just like pulley O¹, its position being similarly fixed by 75 a slotted link R², but it is not adjustable for the purposes of belt tension. That belt-tension is adjusted by means of pulley O¹ alone. The arrangement thus described provides for separate adjustment of the position and 80 of the tension of the belt O. The pulley O² is driven by means of the sprocket chain O³, which is the same chain that drives the brush-wheel shaft F¹.

What I claim as new and desire to se- 85 cure by Letters Patent is:

1. In a bottle washer, a bottle carrier, a belt for rotating bottles supported by said carrier, pulleys for operating said belt, bracket arms, means carried by said bracket arms for adjustably supporting one of said pulleys, means for adjusting said bracket arms toward and from the carrier, and means for supporting the other pulley.

2. In a bottle washer, a bottle carrier, a belt for rotating bottles supported by said carrier, pulleys for operating said belt, bracket arms, means carried by said bracket arms for adjustably supporting one of said pulleys, means for adjusting said bracket arms toward and from the carrier, means for supporting the other pulley, and means for adjusting the last mentioned pulley relative to the carrier.

3. In a bottle washer, a bottle carrier, a belt for rotating bottles supported by said carrier, pulleys for operating said belt, bracket arms, an adjustable support carried by said arms and provided with means for supporting one of said pulleys, means for adjusting said support to tighten the belt, means for adjusting said bracket arms toward and from said carrier, and means for supporting the other pulley.

4. In a bottle washer, a bottle carrier, a belt for rotating bottles supported by said carrier, pulleys for operating said belt, bracket arms, a yoke pivotally supported by said arms and provided with bearings for one of said pulleys, an adjusting screw for regulating the position of said yoke, means for adjusting said bracket arms toward and from said carrier, and means for supporting the other pulley.

5. In a bottle-washer, the combination 125 with a rotating bottle-carrier, of a rotating brush, means for pressing the bottles against the brush and rotating them in contact therewith, a separate brush located adjacent to the neck of the bottle, a projection on the 130

brush for suspending it, and a weight for pressing the brush against the neck of the bottle.

6. In a bottle-washer, the combination 5 with a rotating carrier-wheel and bottle-spindles thereon, of a rotating brush, a standard located adjacent to the said carrier-wheel and brush, movable bracket arms mounted on said standard, pulleys mounted 10 in said bracket arms, one of the pulleys being adjustable thereon, means for fixing the position of said bracket-arms with respect to the bottles, means for fixing the position

of one of said pulleys with respect to the bracket-arm in which it is mounted, and a 15 belt extending around said pulleys and bearing on the bottles while they are in contact with said brush.

In witness whereof I have hereunto set my hand, before two subscribing witnesses, 20 this 19th day of August, 1914.

CHARLES HAMANN.
